POT HOLDER

Carl C. Wilm, Denver, Colo., assignor to Magnex, Inc., Denver, Colo., a corporation of Colorado

Application July 22, 1952, Serial No. 300,135

3 Claims. (Cl. 16—116)

1

The present invention relates to improvements in pot holders, hot pads and the like.

In pot holders, hot pads and similar articles of the prior art, various means have been provided in order that the holder or pad could be held on a hook or other suitable support. Usually, one corner of the holder or pad was provided with a small loop of the same material from which the pad is made or possibly from a piece of some other material. In other types of holders or pads no means whatever is provided for supporting the holder or pad and such holders or pads must be positioned on any supporting surface such as is available in a kitchen, including a stove top or a sink counter.

Various objections and difficulties arise with regard to pot holders and hot pads such as have been described hereinbefore. For example, where a loop has been provided as a means for engagement on a hook or the like, the loop has been too small for easy engagement on a hook and it usually requires both hands, one to hold the holder and the other to open the loop which when made of fabric is usually closed, in order to engage the holder or pad on a hook. A further difficulty arises with regard to the holders or pads employing loops and that is that the loops are first to become worn or ripped, thereby affording no means by which the holder or pad can be engaged on a hook. In those forms where no loop has been provided or the loop has ripped apart, the holder or pad is continually positioned on the stove top or sink counter between uses and is, therefore, subject to being stained such as by grease on the stove top or any food particles that may be collected on the sink counter while cooking. Naturally, the life of such holders or pads is substantially shortened and their desirability for the purpose intended thereby reduced.

It is, therefore, a primary object of the present invention to provide an improved pot holder or hot pad which will not have the objections of the prior art holders and pads, improved means being provided for supporting the holder on any suitable metallic surface available in a kitchen or wherever the holder is being employed.

It is another object of the present invention to provide an improved means whereby a pot holder or hot pad can be held between uses and wherein the means will have a life at least equal to that of the holder proper.

A further object of the present invention is to provide an improved pot holder supporting means which is inconspicuous in use and yet which does

2

not interfere with the practicability of the holder for its intended purpose nor unduly increase the weight of the holder.

Still another object of the present invention is to provide an improved pot holder and supporting means incorporated therein which does not require any tedious manipulation to leave the same supported for subsequent use.

In accordance with the objects of my invention I have provided in a pot holder a small oblong magnet whereby the pot holder can be held by any suitable metallic surface available in a kitchen, such as, for example, the stove front or the doors of metal kitchen cabinets and the like. In the quilted form of pot holder, the magnet is embedded in the cotton batting between the stitchings joining the cloth facings together and adjacent one edge or corner of the pot holder. The corner near which the magnet is disposed is formed with the side edges joining at right angles whereas all of the other edges are distinguished by rounded corners so that when it is desired that the pot holder be held by a metallic surface, the holder can be casually projected against and held by the surface if the holder is manipulated so that the portion near the sharp corner strikes the supporting surface.

In the accompanying drawings is shown a preferred embodiment of my invention, wherein:

Figure 1 is a top plan view of a quilted pot holder showing the disposition of the magnet therein;

Figure 2 is a vertical sectional view taken substantially along the plane of line 2—2 of Figure 1;

Figure 3 is a diagrammatic showing of the manner in which a pot holder can be manually projected toward a supporting metallic surface and held thereby; and

Figure 4 is an enlarged detail perspective view of a pair of the oblong magnets, one of which is employed with each holder.

Having reference to Figures 1 and 2 of the drawings, the details of construction of the pot holder designated generally by the numeral 10 will now be described. The pot holder 10 includes front and rear cloth or fabric panels 12 and 14, respectively, of substantially rectangular shape but having rounded corners at 16, 18 and 20 and a sharp corner at 22. Inserted between the cloth panels 12 and 14 is a suitable amount of cotton batting 24 or any other material suitable for insulating in pot holders. Of course, the panels 12 and 14 also may be made from

materials other than cloth. Oil cloth, or any other sheet material formed from a suitable plastic, could be employed. The pair of panels 12 and 14 with the cotton batting therebetween has a plurality of crossed lines of stitching 24 and 26 joining the same so as to provide a quilted effect.

The periphery of the holder is provided with an inner binding strip 28 which is secured in enveloping relation to the edges of the front and rear panels by a line of stitching 30. An outer binding strip 32 envelopes the inner binding strip 28 and is secured to the inner binding strip and the front and rear panels by a line of stitching 34. Each of the binding strips is made from a single elongated and folded piece of material, preferably cloth, provided with suitable coloring or design for contrast or harmony with the design or coloring that may be provided on either of the panels 12 and 14.

Looking now at Figure 4, the form of the magnets 36 will be seen to be generally rectangular in cross section and oblong. The magnets are formed preferably by casting a plurality of elements at a single pouring, the individual magnet elements 36 being connected by frangible joints, as at 38. As required, the individual magnets are broken from each other so as to provide a rough face 40 at each fracture. The upper and lower faces 42 and 44, respectively, of the magnets 36 are substantially smooth.

When the magnets are individually cast or otherwise formed, one or more of the faces thereof should be roughened as the face 40 for a purpose to be described more fully hereinafter.

In actually manufacturing pot holders of the present type, large sheets of the quilted material are formed and then cut to the shape as shown in Figure 1. At this point in the manufacture it is desirable to incorporate a single magnet, each magnet being sufficiently powerful to hold a single holder on a vertical metallic surface whether projected or positioned thereagainst, into the holder. In cutting the quilted material access into the enclosed areas or pockets formed by the lines of stitching 24 and 26 at the edge portions of the holder is obtained, as at 46 into the minor enclosed area 48. A single magnet 36 is inserted through the access opening at 46 and positioned in a pocket in the padding so as to have its longitudinal axis parallel to the adjacent edge 50. The binding strips may then be stitched to the periphery of the holder 10 in the manner above described.

In view of the nature of cotton batting and the fact that each magnet has at least one roughened face 40, the magnet will effectively be held in position as a result of the interlocking of the fibers of the batting 24 with the projections of the roughened face 40. Furthermore, the lines of stitching 24 and 26 retain the magnet in the pocket in the padding and in the desired relation to the holder. Other modes of securing the magnet in position will suggest themselves to one skilled in the art.

As shown by Figure 3, after using the pot holder 10, it can be projected, as seen in dotted lines, so that the sharp corner portion 22 is disposed upwardly whereby upon contact with the metallic surface 52 it is retained thereagainst by the magnetic attraction between the magnet 36 and the surface 52 and will be held from swinging movement by the friction between the holder and the surface, which friction is, of course, dependent upon the strength of the magnet 36.

I prefer to have the front cloth panel 12 provided with a suitable appealing and decorative design and to have the rear panel of a solid color so as to be indicative of the back side adjacent which the magnet is disposed, as shown best in Fig. 2. By locating the magnet in contact with the rear panel 14 and projecting the holder so that the panel 14 will strike the surface 52, the greatest effective use of the magnet can invariably be obtained. It will thus be seen that by means of the present invention the pot holders can be held on metal kitchen cabinet doors and the like for convenience and yet will add decoration by their design or variable arrangement on the doors. If desired, the front panel can have designs of appeal to children so as to afford amusement to them when playing with the holders.

It is desirable that the magnet be rust proof and relatively powerful for its size and, therefore, Alnico magnets are particularly suitable. The magnet actually used is approximately $\frac{3}{4}$ " in length, $\frac{3}{8}$ " in width and $\frac{1}{8}$ " in thickness. Of course, variations in the size and shape of the magnet can be made.

I claim:

1. A pot holder comprising sheets of fabric with fibrous padding therebetween secured together and quilted to provide a minor enclosed area substantially filled with padding, said padding in that area providing a pocket in one corner of the holder, and a magnet positioned in said pocket and retained against displacement therein by the padding between the sheets.

2. A pot holder according to claim 1, wherein the pot holder has a single sharp corner and the magnet is placed in an enclosed area adjacent said corner and the other corner being rounded so as to indicate the location of the magnet.

3. A pot holder according to claim 1, wherein the magnet has at least one rough face whereby the fibrous padding will become interlocked with the projections of the rough face.

CARL C. WILM.
